Inventor:

Samuel S. Colt

UNITED STATES PATENT OFFICE.

SAMUEL S. COLT, OF ORANGE, NEW JERSEY.

BEVEL AND MITER.

SPECIFICATION forming part of Letters Patent No. 322,906, dated July 28, 1885.

Application filed May 12, 1885. (No model.)

To all whom it may concern:

Be it known that I, SAMUEL S. COLT, a citizen of the United States, residing at Orange, in the county of Essex and State of New Jersey, have invented a new and useful Improvement in Bevels, of which the following is a full, clear, and exact description.

My invention relates to an improvement, whereby the miter forming any angle or bevel to may be indicated by the instrument. I attain this object by means shown in the accompanying drawings, in which—

Figure 1 represents a plan view in perspective of a bevel with my improvements there-to, and Figs. 2 and 3 represent details of construction.

Similar letters refer to similar parts throughout the several views.

A is the body or handle of a bevel; B, the slotted blade, and b the thumb set-screw to hold the slotted blade B in position.

My improvements comprise the guide c, as shown in Fig. 2, movable backward or forward within the slotted blade B, and held in position by the thumb set-screw b, the blade B, with the guide c, rotating on the thumb set-screw b, as shown. The guide c has a mark, e, on the periphery forming the circular part to denote the position of blade B with the scale D.

The ends of body or handle A are rounded off to form a half-circle and laid out in spaces or degrees and numbered, forming a scale, as

shown at D and E. On the lower end of body or handle A is a blade, C, which is held in position by the thumb set-screw a, and rotates thereon. The blade C has a mark, d, on the edge to denote its position with the scale E.

To operate the instrument, when both blades B and C are closed up within the body or handle A, the mark e on the guide c, within the slotted blade B, and the mark d on the edge of blade C will point to the number 0 on their respective scales D and E. Then set the slotted blade B in position with the body or handle A to form a right angle thereto. Set the thumb set-screw b firmly. Turn the instrument to read the position of the slotted blade B with the scale D, and note the number. Then set the blade C to the corresponding number on the scale E. Set up the set-screw a firmly, which will give the true miter, and a similar result with any angle or bevel that may be required.

Having fully described my invention, what I claim as new, and desire to secure by Letters Patent, is—

The guide c, the blade C, set-screw a, scale D and E, index e and d, in combination with the handle A, slotted blade B, and set-screw b, of a bevel, all substantially as set forth.

SAMUEL S. COLT.
